COMBINATION TRASH RECEPTACLE AND BURNER UNIT

Oscar Samuelson, Baltimore, Md.

Application July 21, 1952, Serial No. 299,959

3 Claims. (Cl. 110—19)

The present invention relates to a combination trash receptacle and burner unit. More particularly, the present invention relates to a combination trash receptacle and burner unit which is adapted to have trash or leaves swept therein for disposal thereof.

Prior to the instant invention, various devices and means have been employed by the home owner for disposing of leaves and trash that accumulate on the lawn or in the yard surrounding the home. The heretofore known conventional trash burner or incinerator generally consisted of the type which was suitably positioned in the yard and which was adapted to receive the trash or leaves through an opening in the top thereof. However, such receptacles necessitated expending considerable labor since the accumulated rubbish had to be manually picked up from the ground and deposited in the receptacle opening. Moreover, these heretofore known trash disposal devices were bulky, difficult to maneuver and were a definite eyesore to the community at large.

It is an object of the present invention to provide a compact combination receptacle and burner unit into which trash or leaves are swept for disposal thereof.

Another object of the present invention is to provide a compact combination trash receptacle and burner unit which includes a box-like structure on which are located oppositely hinged doors.

Still another object of the present invention is to provide a receptacle for trash and leaves which is supported by a base having slanted portions.

Other objects and the nature and advantages of the instant invention will be apparent from the following description taken in conjunction with the accompanying drawings, wherein:

Fig. 1 is a perspective view of two of the combination receptacle and burner units embodying the present invention disposed in side-by-side relation;

Fig. 2 is a vertical sectional view of one of the combination receptacle and burner units illustrated in Fig. 1, showing one of the doors in the open position;

Fig. 3 is a view taken along the line 3—3 of Fig. 2;

Fig. 4 is a modification of the invention showing a partial view of two of the units in side-by-side position; and Fig. 4a is a fragmentary enlarged view in perspective of the upper central portion of Fig. 4.

Referring to the drawings, the combination trash receptacle and burner unit embodied in the present invention includes a base and box-like burner enclosure indicated generally at 10, 12, respectively. Each of the receptacle units is adapted to be employed individually or, if desired, may be utilized in groups of two or more. If two or more units are employed, they may be positioned at opposite ends of the area to be cleaned, or if the rubbish is present in large quantities at one particular location, the units can be positioned directly adjacent one another, thereby increasing the disposal space.

Referring now to Fig. 1, two of the combination trash receptacle and burner units are shown positioned in side-by-side relation. The base 10 included in each unit is

2

preferably constructed from a heat-resistant material which is adapted to resist the heat resulting from the fire when the trash or leaves are burned thereon and thereby is adapted to protect the ground area immediately below the unit. Referring to Fig. 2, the base 10 is shown hollow in construction and formed with front and rear walls 14 and 16, which are inclined upwardly and inwardly toward each other. The inclined walls 14 and 16 are located on opposite sides of the base 10 and are formed so as to facilitate sweeping of the trash or leaves into the interior of the unit. Side walls 18, 20 of the base 10 are vertically disposed, thereby enabling the unit to be snugly placed adjacent a companion unit as illustrated in Fig. 1. The base is completed by a top wall 22, which is formed integral with the side and front base walls and which is adapted to serve as the floor of the unit.

Located on the base 10 is the burner enclosure 12 which is adapted to be conveniently lifted therefrom if it is desired to move the unit to another position. The burner enclosure 12 is constructed from a heat-resistant expanded metal material in a box-like configuration and includes a top section 24. The top section 24 folds over into integral side sections 26, 28 which are formed at right angles thereto. The side sections 26, 28 in turn fold over to form the abbreviated bottom sections 30, 32. The abbreviated bottom sections 30, 32 extend the length of the side sections 18, 20 and are adapted to support the enclosure burner 12 on the top portion 22 of the base 10. Hingedly secured to the burner enclosure top section 24 by suitable means, such as rings, 34, are front and rear doors 36, 38. As shown particularly in Figs. 1 and 2, when the unit is to be filled with trash or leaves, either of the doors 36, 38 may be swung upwardly on the rings 34 to a position on the top of the box-like burner enclosure.

Referring to Fig. 4 and Fig. 4a, a modification of the burner enclosure is illustrated wherein in addition to the front and rear doors 36, 38 being hinged to the enclosure by rings, the side sections 26, 28 are each hingedly secured to the top section 24 by suitable rings, such as indicated at 34. It is apparent that with this construction, two of the units can be placed in side-by-side position and the adjacent side sections folded upwardly. This arrangement eliminates the middle partition between the side-by-side units and provides a single enclosed space. With the units in this position, either the front door 36 or the rear door 38 is folded upwardly whereby the trash or leaves can be easily swept into the burner enclosure, unimpeded by any middle wall.

The trash receptacle and burner unit is utilized in the following manner:

The base 10 is positioned on the ground at the desired location and the box-like burner enclosure 12 placed thereon. Either of the doors 36, 38 is then swung upwardly, depending on from which side of the unit it is desirable to sweep the trash or leaves. As shown in Figs. 1 and 2, the door 36 is in the open position, having been swung upwardly on the rings 34 to a position on top of the burner enclosure 12. With the door 36 in the open position, leaves or trash or other litter is then swept up the slanted front section 14 of the base 10 into the interior of the enclosure 12. If it is necessary, the door 36 can be closed and the door 38 opened. The leaves or trash on the side adjacent the door 38 can then be swept up the slanted rear wall 16 of the base 10 into the interior of the box-like burner enclosure 12. When the enclosure 12 is sufficiently filled, the doors 36 and 38 are closed and the leaves or trash ignited and burned for quick disposal thereof.

If it is more convenient, the burner enclosure 12 may be removed from the base 10 and the trash or leaves swept into a pile on top of the open base 10. When all of the available leaves or trash are deposited or swept onto

the open base 10, the enclosure is then placed on top of the base, thereby completely enclosing the trash or leaves which are then ignited and burned.

It may on occasion be desirable to utilize the box-like burner enclosure 12 without the base 10, such as, for example, when the ground is to be a permanent foundation for the enclosure or if a stone foundation is available. In these situations, it may be advantageous to dispense with the base 10. However, it is apparent that the use of the unit is the same in any instance.

It is apparent that the combination trash receptacle and burner unit described hereinabove discloses a device for simply and efficiently disposing of trash and leaves. Moreover, the unit is portable and can be moved from one position to another, as desired. Any number of the units may be employed either individually at advantageous positions, or in side-by-side relation, as shown in Fig. 1. It is also understood that the burner enclosure 12 may be fabricated in various sizes depending on the use for which it is employed.

It is apparent from the above description that the trash receptacle and burner unit will enable a home owner to keep the yard or lawn free of leaves and trash with a minimum of effort. Furthermore, the burner enclosure 12 confines the fire to a limited area which is desirable from a safety point of view.

It will be obvious to those skilled in the art that various changes may be made without departing from the spirit of the invention and, therefore, the invention is not limited to what is shown in the drawings and described in the specification, but only as indicated in the appended claims.

What is claimed is:

1. In a combination trash receptacle and burner unit, a base being defined by front, rear, side and top walls, said front and rear walls being inclined upwardly and inwardly toward each other, a removable and portable box-like burner enclosure disposed on said base, the top wall of said base thereby forming the bottom of said burner enclosure, said burner enclosure including oppositely disposed front and rear doors, said front and rear doors extending to said base and swinging open to expose the

interior of said burner for the introduction of trash or leaves therein, said trash or leaves thereafter being burned in said enclosure.

2. In a combination trash receptacle and burner unit, a base comprising front, rear, side and top walls, a removable and portable box-like burner enclosure disposed on said base, said enclosure including hinged doors extending to said base, said base side walls being vertical and said front and rear walls thereof being inclined upwardly and inwardly toward each other to form inclined surfaces for enabling trash to be swept into the interior of said enclosure, said doors being positioned above said inclined surfaces, and one of said doors being hinged openable to expose the interior of said burner.
- 5 3. In a combination trash receptacle and burner unit, a base having front and rear walls inclined upwardly and inwardly toward each other, and a top wall joined to said front and rear walls, and a portable burner enclosure disposed on said base, said burner enclosure including oppositely disposed front and rear doors extending to said base, each of said doors swinging open to expose the interior of said burner enclosure, said burner enclosure being manually removable from said base to expose the top wall thereof.
